UNITED STATES PATENT OFFICE.

AUSTIN FREDK. JACKSON, OF TAUNTON, MASSACHUSETTS, ASSIGNOR TO REED & BARTON, OF SAME PLACE.

DESIGN FOR A FORK, SPOON, &c.

SPECIFICATION forming part of Design No. 15,271, dated August 19, 1884.

Application filed June 6, 1884. Term of patent 7 years.

To all whom it may concern:

Be it known that I, AUSTIN F. JACKSON, a subject of the Crown of Great Britain, residing at Taunton, in the county of Bristol and State of Massachusetts, have invented and produced a new and original Design for a Fork, Spoon, &c., of which the following is a specification, reference being had to the accompanying photographic illustration, forming part thereof, in which—

Figure 1 is a front, and Fig. 2 a back, view. My design, which is intended for the handles of forks, spoons, &c., consists in the shape or outline of the handle, and also in the superficial ornamentation. The handle in outline swells with a very gradual taper from the shank *a* to a point, *b*, near the end, where it attains the greatest width, which, however, is less than the usual width, and from this point *b* to the end there is a slight inward taper or reduction of width, which runs to the nearly-square but slightly-rounded end *c*. Between

the point *b* and the shank there is on the front side a surface-ornamentation consisting of a mask or face, *d*, and below it a flowering-vine, *e*, each inclosed by ornamental border-lines. On the reverse side of the handle there is, near the end, a transverse band, *f*, of scalloped design, and at the shank *a* are longitudinal flutes *g*, crossed by a band, *h*.

What I claim is—

1. A design for the handles of forks, spoons, &c., consisting of a gradually-tapered and unbroken outline having a slight contraction beyond its widest point, *b*, and an abrupt and nearly square or straight end, *c*.
2. A design for the handles of forks, spoons, &c., consisting of a smooth or plane surface at *b*, a face or mask, *d*, and vine *e*.

AUSTIN FREDK. JACKSON.

Witnesses:

ELISHA T. JACKSON,
F. E. FISKE.
